RAYMOND STUART WAY, OF LOS ANGELES, CALIFORNIA, ASSIGNOR OF ONE-HALF TO
CHARLES W. PRESSLEY, OF LOS ANGELES, CALIFORNIA.

FOLDABLE GAS-STOVE.

1,092,681.

Specification of Letters Patent.

Patented Apr. 7, 1914.

Application filed September 26, 1912. Serial No. 722,435.

To all whom it may concern:

Be it known that I, RAYMOND STUART WAY, a citizen of the United States, and a resident of Los Angeles, in the county of 5 Los Angeles and State of California, have invented a new and Improved Foldable Gas-Stove, of which the following is a full, clear, and exact description.

The invention relates to gas cooking stoves, and its object is to provide a new and improved gas stove adapted to be folded into a casing set in a recess in a wall, to take up comparatively little room or not detract from the appearance of the apartment, to allow of conveniently and quickly unfolding the stove for use, and to automatically shut off the gas supply when folding it into the casing or to turn on the gas supply when moving the gas stove into extended position. For the purpose mentioned, use is made of a casing set in a recess in the wall, a support pivoted in the lower portion of the casing and adapted to fold therein or to rest on the said support when the latter is extended.

A practical embodiment of the invention is represented in the accompanying drawings forming a part of this specification, in which similar characters of reference indicate corresponding parts in all the views.

Figure 1 is a perspective view of a folding gas stove as applied and in extended position, part of the wall and part of the hood of the gas stove being broken out; Fig. 2 is 35 a front elevation of the folding gas stove with the parts in folded position; Fig. 3 is an enlarged cross section of the same; Fig. 4 is an enlarged sectional plan view of one of the trunnions of the gas stove and the valve 40 for turning the gas on and off, the section being on the line 4-4 of Fig. 5; Fig. 5 is a cross section of the same on the line 5-5 of Fig. 4; and Fig. 6 is a similar view of the 45 same with the parts in position for turning off the gas.

In a recess in the wall A of an apartment, kitchen or the like is set a casing B provided with a flange B' resting against the face of the wall, as plainly indicated in Fig. 1. A 50 support C in the form of a table or the like is connected by pivots C' with the sides of the casing B at the lower portion thereof so that the said support C can be swung outward into horizontal position, as shown in Fig. 1, or can be swung upward and into the

casing B, as illustrated in Fig. 3. Hinged links D connect the sides of the support C with the sides of the casing B to hold the support C in an extended position. On the sides of the support C are arranged extension supports E in the form of tables connected by hinges E' with the said sides of the support C to form side extensions thereof, each side extension support E being held in extended position by the use of a chain F attached at F' to the flange B' of the casing B and detachably connected to a hook F² held on the outer side of the corresponding extension support E. The extension supports E when disconnected from the chains F can be folded against the under side of the support C to be folded with the latter within the casing B when the device is not in use.

On the top of the support C when extended are adapted to rest the legs G' of a gas cooking stove G, of any approved construction, to permit of using the gas cooking stove in the usual manner. The gas cooking stove G is mounted to swing on 75 trunnions H and H², of which the trunnion H² is fixed on the gas stove and engages a bearing in one side of the casing B, while the other trunnion H is connected by a coupling I' with a gas supply pipe I 80 connected with a suitable source of gas supply. The burner pipe G² of the gas cooking stove G terminates in a bearing G³ mounted to turn on the trunnion H, and the said bearing G³ is provided with a port G⁴ 85 adapted to register with a port H³ formed in the trunnion H at the time the gas cooking stove G is in extended position and rests on the extended support C. When the gas cooking stove G is swung upward and inward in the casing B then the bearing G³ turns on the trunnion H whereby the port G⁴ moves out of engagement with the port H³ and the gas is cut off from the burner pipe G² of the cooking stove G (see Fig. 6). 90 The bearing G³ may be split, as indicated in Figs. 4, 5 and 6, to permit of tightly fitting the bearing on the trunnion H to prevent leakage of gas. A hood J is connected by a hinge K with the upper front end of 95 the casing B, and the sides of the hood J are connected by links L with the rear members of the hinged links D so that when the parts are in extended position the hood J is held approxi- 100 105 110

mately in a horizontal position above the gas cooking stove G, so that any odors arising during the cooking operations strike the hood J and are deflected by the latter into the casing B, from the top of which leads a vent pipe N to carry off the odors to a suitable place of discharge, the vent pipe N extending through the wall A. When the support C and the cooking stove G are in folded position within the casing B then the hood J overlies the support C and its extension supports E at the same time forming a cover for the casing B, as illustrated in Figs. 2 and 3. Suitable locking means O are provided for holding the hood J in folded and closed position, as indicated in Fig. 2.

The links L are pivotally connected with the rear members of the links D, and their ends engage recesses J' in the under side of the hood J, so as to support said hood in horizontal position or to be disengaged therefrom to permit of folding the hood.

A drip pan P is placed under the stove G and rests on the support C to catch any drippings during the cooking operation. The drip pan is provided at its rear with an upturned flange to catch drippings when the stove is folded up.

It will be noticed that when the stove parts are in folded position, as shown in Figs. 2 and 3, no projections are had in the apartment in which the stove is located, and hence the folded stove does not detract from the appearance of the apartment. When it is desired to use the stove it is only necessary to unlock the hood J to swing the same upward into open position and to swing the support and the stove G outward into extended position, as shown in Fig. 1, to permit of using the gas stove in the usual manner for cooking purposes.

It is understood that when the parts are folded the gas supply is shut off from the burner pipe G², but when the parts are in extended position the gas is automatically turned on to supply the burner pipe G² with gas. It will also be understood that since the support C and the stove G are independently mounted the stove may be swung into the casing and the support serve as a shelf for other purposes.

Having thus described my invention, I claim as new and desire to secure by Letters Patent:

1. A foldable gas stove, comprising a casing adapted to be set into a recess in a wall, a support pivoted on the lower portion of the said casing and adapted to fold therein or be extended horizontally therefrom, a gas stove pivoted in the lower portion of the said casing independent of the support and adapted to fold therein or when extended to rest on the said support, and means whereby the gas supply will be cut off when the

stove is folded and turned on when the stove is extended.

2. A foldable gas stove, comprising a casing adapted to be set into a recess in a wall, a support pivoted on the lower portion of the said casing and adapted to fold therein or be extended horizontally therefrom, a gas stove pivoted in the lower portion of the said casing and adapted to fold therein or when extended to rest on the support, and a hood pivoted on the top of the casing for forming a cover for the same or when extended forming a hood for the said gas stove.

3. In a foldable gas stove, the combination with a wall, having a recess therein, of a pivoted support, hinged links for holding the support in a horizontal position, and a gas stove pivoted independently of the support and adapted to rest upon the said support when in use and to fold into the recess in the wall when not in use so that the support may serve as a shelf for other purposes.

4. In a foldable gas stove, the combination with a wall having a recess therein, of a pivoted support, a pivoted gas stove adapted to rest on the said support and to fold with the said support into the recess in the wall, the support when folded covering the folded stove, and a pivoted hood adapted to extend over the said gas stove when the latter and the support are in extended position and to cover the said support when the latter and the gas stove are in folded position.

5. A foldable gas stove, comprising a casing adapted to be set into a recess in a wall, a support pivoted on the lower portion of the said casing and adapted to fold therein or be extended horizontally therefrom, a gas stove pivoted in the lower portion of the said casing and adapted to fold therein or when extended rest on the said support, side extension supports hinged to the sides of the said support and adapted to be folded thereon, and flexible means detachably connecting the said side extensions with the said casing.

6. A foldable gas stove, comprising a casing adapted to be set into a recess in a wall, a support pivoted on the lower portion of the said casing and adapted to fold therein or be extended horizontally therefrom, a gas stove pivoted in the lower portion of the said casing independent of the support and adapted to fold therein or when extended to rest on the said support, means for holding the support in a horizontal position and folding with said support into the casing, and means for supplying the said gas stove with gas, the said means having a cut-off valve adapted to open on swinging the gas stove into extended position, and adapted to close on folding the gas stove into the casing.

7. A foldable gas stove, comprising a casing set in a recess in a wall and provided with a vent pipe, a support pivoted to the

lower front portion of the said casing to extend horizontally therefrom or to fold into the casing, hinged links connecting the said support with the said casing to hold the support in an extended position, a gas stove provided with trunnions having bearings in the lower side portions of the said casing to allow of folding the said gas stove into the casing and to allow of swinging the gas stove outward to rest on the said support, one of the said trunnions being hollow and connected with a source of gas supply, and a valve in the said hollow trunnion and adapted to open on swinging the gas stove outward into position of use, and adapted to close on swinging the gas stove into folded position in the casing.

8. A foldable gas stove, comprising a casing set in a recess in a wall and provided with a vent pipe, a support pivoted to the lower front portion of the said casing to extend horizontally therefrom or to fold into the casing, hinged links connecting the said support with the said casing to hold the support in an extended position, a gas stove provided with trunnions having bearings in the lower side portions of the said casing to allow of folding the said gas stove into the casing and to allow of swinging the gas stove outward to rest on the said support, one of the said trunnions being hollow and connected with a source of gas supply, a valve in the said hollow trunnion and adapted to open on swinging the gas stove outward into position of use and adapted to close on swinging the gas stove into folded position in the casing, a hood hinged to the upper front portion of the casing and adapted to cover the said support when both are in folded position, links pivotally connected with the said hinged links and engaging the said hood, side extension supports hinged to the sides of the said support and adapted to be folded thereon, and flexible connections detachably connecting the said casing with the said side extension supports.

In testimony whereof I have signed my name to this specification in the presence of two subscribing witnesses.

folded position, and links pivotally connected with the said hinged links and engaging the said hood.

9. A foldable gas stove, comprising a casing set in a recess in a wall and provided with a vent pipe, a support pivoted to the lower front portion of the said casing to extend horizontally therefrom or to fold into the casing, hinged links connecting the said support with the said casing to hold the support in an extended position, a gas stove provided with trunnions having bearings in the lower side portions of the said casing to allow of folding the said gas stove into the casing and to allow of swinging the gas stove outward to rest on the said support, one of the said trunnions being hollow and connected with a source of gas supply, a valve in the said hollow trunnion and adapted to open on swinging the gas stove outward into position of use and adapted to close on swinging the gas stove into folded position in the casing, a hood hinged to the upper front portion of the casing and adapted to cover the said support when both are in folded position, links pivotally connected with the said hinged links and engaging the said hood, side extension supports hinged to the sides of the said support and adapted to be folded thereon, and flexible connections detachably connecting the said casing with the said side extension supports.

In testimony whereof I have signed my name to this specification in the presence of two subscribing witnesses.
